UNITED STATES PATENT OFFICE.

GUSTAV GOLDBACH, OF DOMSLAU, GERMANY.

ATTACHMENT FOR HARNESS-TRACES.

No. 926,249.

Specification of Letters Patent.

Patented June 29, 1909.

Application filed September 12, 1908. Serial No. 452,711.

To all whom it may concern:

Be it known that I, GUSTAV GOLDBACH, a subject of the German Emperor, residing at Domslau, Silesia, in Germany, have invented 5 certain new and useful Improvements in Attachments for Harness-Traces, of which the following is a specification.

This invention consists in an easily releasable coupling for the attachment of harness 10 traces to the ends of the whiffle tree or equivalent part of the vehicle to which traces are intended to be secured.

In the annexed drawing Figure 1 is a plan of the coupling, Fig. 2 a side elevation in 15 open position and Fig. 3 a side elevation in closed position.

The coupler consists of a pair of jaw levers b , b' pivoted at their inner ends to each other and to a whiffle tree bar or equivalent 20 part a by means of a pivot bolt a' passed through a pair of spaced lugs a^2 projecting from said bar a . The outer ends of the jaw levers b are curved in opposite directions and when brought together form a ring-shaped mouth b' adapted to engage a ring on the end of a trace or equivalent device. The intermediate portions of said jaw levers b are straight and between these straight 25 portions and their pivoted inner extremities 30 are oppositely projecting curved portions or loops b^4 within which a spring c is arranged for forcing the jaw levers apart.

On the upper face of the straight portion 35 of the lower jaw lever is an integral hook d formed in its outer edge with a notch d' , and in the corresponding portion of the upper jaw lever is formed a slot e to receive said hook d when the mouth portions b' of the 40 jaw levers are closed.

Formed in the upper jaw lever and extending longitudinally so as to intersect the transverse slot e is a slot f which serves as a guide for a sliding bolt i adapted to enter the notch d' in the hook or lug d . The bolt 45 i is pivoted between the outer ends of two links g arranged on opposite sides of the upper jaw lever and having their inner ends pivoted at g' to the intermediate portions of the angular arms of a U-shaped lever h . The 50 ends of the arms of this lever h are pivoted at h' on opposite sides of the upper jaw lever and said lever h is of such shape that it is adapted to swing over the loop b^4 of said

upper jaw lever and carry the pivots g' inwardly past the longitudinal center of the 55 pivots h' , as shown in Fig. 3 of the drawings, and thereby lock the bolt i in its operative position within the notch d' of the hook d . When the lever h is swung to its position shown in Fig. 2 the bolt i is retracted to release the hook or lug d and thereby permit the spring c to open the device. The meeting ends of the mouth portions or loops b' of the jaw levers are preferably made with a projection and recess b^2 , b^3 , respectively, 60 to engage one another for more effectively coupling the jaw levers when the device is closed.

What I claim as my invention and desire to secure by Letters Patent of the United 70 States is:

1. A harness trace coupling comprising, in combination, two pivoted jaw levers having curved ends shaped to form a ring-shaped mouth when the device is closed, one 75 of said jaws having a slot, a spring interposed between said jaw levers, a hook upon the other of said jaw levers adapted to enter said slot, a longitudinally movable bolt in the slotted jaw lever to engage said hook, 80 a U-shaped lever having its arms pivoted at their ends on opposite sides of said slotted jaw lever and links connecting the intermediate portions of the arms of the U-shaped lever to said bolt, the pivots uniting 85 the links to the arms of the U-shaped lever being adapted to pass the longitudinal plane of the pivots of said arms of the lever, for the purpose set forth.

2. A harness trace coupling comprising, 90 in combination, two jaw levers pivoted together at their inner ends and having curved outer ends shaped to form a ring-shaped mouth when the levers are brought together, the latter having straight intermediate portions, one of which is formed with a transverse slot, the last mentioned jaw lever being also formed with a longitudinal slot intersecting said transverse slot, a lug upon the intermediate portion of the 95 other jaw lever and adapted to enter said transverse slot, said lug being formed with a notch to register with said longitudinal slot, a sliding bolt in said longitudinal slot, a spring interposed between said jaw levers, 100 a U-shaped lever to straddle one of the jaw

levers and having its arms pivoted at their ends to said jaw lever and links connecting the intermediate portions of the arms of said U-shaped lever to said sliding bolt, the 5 pivots uniting the links to said U-shaped lever being adapted to pass the longitudinal plane of the fulcrum points of said lever, for the purpose set forth.

In witness whereof I have signed this specification in the presence of two wit- 10 nesses.

GUSTAV GOLDBACH.
